BELT LOADER

Arthur L. Bureau, United States Navy

Application November 5, 1943, Serial No. 509,081

16 Claims. (Cl. 86—48)

(Granted under the act of March 3, 1883, as
amended April 30, 1928; 370 O. G. 757)

1

This invention relates to improvements in power belt loading machines and has particular reference to a novel machine of this character having a selector wheel with changeable tripping pins by means of which various combinations of ball and tracer ammunition may be belted. Machines generally intended for automatically loading disintegrable belts with various types of ammunition are disclosed in my copending applications filed August 4, 1942, Serial No. 453,545, which has matured into Patent No. 2,397,944, and filed February 2, 1943, Serial No. 474,452.

The machine of the first application, briefly summarized, has twin ammunition feed chutes from which ball and tracer rounds are mechanically delivered to a common ramming point in a fixed ratio, while the machine of the second application has a single feed chute in which any desired ratio of tracer to ball rounds is established by continuous manual emplacement of the rounds of both kinds. In the present machine, the ball and tracer rounds are supplied by twin chutes, but the ratio of one to the other can be altered by merely regrouping the tripping pins through the medium of which the rounds are released.

The new loading machine affords several advantages which will meet a current need: first, the avoidance of having to adhere to a prescribed tracer to ball ammunition ratio; second, the elimination of the uncertainty of maintaining the accurate manual interspersion of tracer rounds in any adopted ratio; and third, the facility with which the machine can be changed from one ratio of feed to another and then continue to function automatically without any other manual attention than to keep the respective chutes supplied with ammunition of both kinds.

Therefore, an object of the invention is to provide a cartridge belting machine having means which can be set in a relatively short time to cause an automatic feeding of any one of a limited number of ratios of tracer to ball rounds of ammunition, for example, one tracer to three ball rounds, one tracer to five ball rounds, one tracer to seven ball rounds, etc.

Another object of the invention is to employ a selector wheel and a system of variously combinable tripping pins for the purpose of periodically releasing the rounds of ammunition, the ratio of one type of ammunition to the other being determined by the order of permutation of the tripping pins.

Another object of the invention is to actuate the selector wheel simultaneously with each ramming stroke thereby to release a round with each stroke

2

and insure the continuity of the supply of rounds in the ramming chamber.

Other objects and advantages will appear in the following specification, reference being had to the accompanying drawings, in which

Fig. 1 is a perspective view of the improved belting machine showing it mainly from the front;

Fig. 2 is a perspective view of the selector wheel and shutter assemblage;

Fig. 3 is a perspective view of the selector wheel actuating cam;

Fig. 4 is a perspective view of a bracket hereinafter referred to;

Fig. 5 is a perspective view of the machine, again showing it from the front but from the end opposite to Fig. 1;

Fig. 6 is a perspective view of the back check device for the link belt, but with cam plate 95 in its retracted position;

Fig. 7 is a vertical section of the back check device, taken on the line 7—7 of Fig. 1;

Fig. 8 is a partially elevational and sectional view of the selector wheel and associated parts;

Fig. 9 is a detail sectional view of the ammunition magazine, showing one position of the shutters;

Fig. 10 is an end elevation of the magazine, parts being in section, illustrating the action of rocking one of the shutters;

Fig. 11 is an end elevation of the magazine, parts being in section, illustrating the dislodgement of the round upon return of the shutter to its original position;

Fig. 12 is a vertical section of the machine, taken substantially on the line 12—12 of Fig. 8, and

Fig. 13 is a side elevation of a portion of the machine as seen from the rear.

Parts of the instant machine and some parts identified with application Serial No. 474,452 are described as follows: The machine has a base 21 equipped with handles 22 providing convenient grips by which to lift the mechanism for moving it when necessary. An electric motor 23 constitutes the source of power which is delivered to the operating parts of the machine through a gear box or speed reducer 24, the latter being driven by the motor through a shaft 25. A clutch 27 actuated by a handle 28 starts and stops the machine, and in some instances can be used to slow the machine by slipping the clutch. A rod 30, reciprocable by a cam (not shown) inside of the gear box, actuates a mechanism for vibrating the links 46 which gravitate to the load-

55

ing position in a chute 40. The details of this mechanism are disclosed in the application Serial No. 474,452, and are herein shown only to the extent of a bar 50 which is one of a pair of such bars acting on the link column from opposite sides to jog the hinge knuckles into alignment.

An ammunition feed magazine 63 is mounted on the base 21. This magazine comprises two hoppers to which the rounds 64, 64a are delivered from diverging feed chutes 65, 65a and thereupon are ranked in separate erect columns between which the partition structure 66 provides a division (Fig. 9). The structure 66 comprises plates which curve over at the tops, as at 67 (Figs. 5, 8, 12 and 13), to form mouths into which the rounds or the increments of a comparable load are fed from the chutes. The front and rear sides of the magazine converge at 68 into a single outlet 69 communicating with the feed chamber 70 into which the rounds are eventually dropped.

The magazines 63 includes end plates 71, 72 to which the upright edges of the front and rear sides are secured by screws or the like. A bracket 73, secured to the base 21 and to the end plate 71 (Fig. 8) supports that end of the magazine. The other end of the magazine is supported by structure disclosed in the last-mentioned application and which forms no part of the present invention. It is sufficient to state that the structure includes an abutment block 75 against which the links 46 are driven (Fig. 6) in the ramming operation, and a link-advancing slide 80. This slide carries a pawl 81 (Fig. 8).

A cover plate 82 is secured at 83 to the block 75 and extends forwardly therefrom sufficiently far to support a back check or detent device over the emerging cartridge belt. The inner portion of the plate 82 defines part of a housing in which the slide 80 is operable to cause the pawl 81 to advance the links to the ramming position and to push the belt out of the machine step by step.

The forwardly extending portion of the plate 82 carries cylindrical tubes 84, 85 which are arranged in tandem and stand upright, as shown. At the top they are partly closed at 86 to provide abutments for the upper ends of springs 87 therein. These springs bear down upon the shoulders of spherically headed plugs 88 which ride the cartridge belt, as shown in Fig. 7. The spacing of the tubes is such as to superimpose the respective plugs upon the crest of one of the links and upon adjacent link portions in the valley between two adjacent links. Thus a substantial length of completed belt is held in suspension from the belt chute 89. In practice, the advance end of the belt is permitted to hang down over the front edge of the chute, there to be caught in a suitable container. Studs 90 extend up from the plugs 88, occupying openings in the closures 86 and carrying cotter pins 91 which keep the detents in their proper places.

A roller stud 93 (Figs. 6 and 8) projects upwardly from the slide 80 and occupies the cam slot 94 of a plate 95. The plate is reciprocable and since the slot is formed at an angle to the direction of rectilinear motion, it follows that the walls of the slot will produce such cam action on the stud as will reciprocate the slide 80. The cam plate is firmly secured to an upstanding wall 96 of the ramming slide 97. The slide is appropriately guided upon the base 21 in making its rectilinear motions which are imparted thereto from the gearing in the box 24 through suitable linkage.

A ledge 111 is cooperable with a break-link

lever 112, the purpose of which is to check the flow of cartridges through one ramming cycle. This allows a pair of links to go loose and thus cause a break in the belt. The lever is secured to one end of a shaft 113 journaled in bearings 114 which are mounted on one side of the outlet 69. A spring 115 exerts a constant downward pressure on the inner end 116 of the lever, thus tending to keep its pin 117 down and in contact with the top of the slide 97. The position which it then assumes is in a plane immediately below the ledge 111 (Figs. 5 and 8), which is the working or ramming position.

The shaft 113 carries a shutter 120 which normally extends directly downward so as not to interfere with the column of cartridges in the outlet 69. When it is desired to provide a break in the link belt, the lever 112 is pushed down while the ramming slide 97 is at the limit of its ramming stroke. The shutter 120 swings into the magazine and intercepts the cartridges. The pin 117 rides the ledge 111 on the return stroke of the ramming slide, thus supporting the cartridges in the outlet during one ramming cycle.

The structure more directly characterizing the present invention is described as follows: The ball and tracer cartridges 64, 64a are supported in the hoppers of the feed magazine 63 by shutters 121, 122 which have a trough shape. The troughs of the shutters are normally directed downwardly (Fig. 9) so that their upper edges catch and hold the overlying cartridge columns. The shutters are welded off-center lengthwise of rockable shafts 123, 124 which extend horizontally and longitudinally of the magazine in superimposed relationship, the shafts being journaled in the end plates 71, 72 where they are held by set collars 125 (Fig. 12).

The shutters are rockable because of their being secured to the shafts 123, 124. Since the shafts are centered on the vertical partition line of the magazine, the shutters may be considered as centered between the ammunition hoppers. This arrangement requires the shutter troughs to be directed oppositely to each other to serve the respective columns of cartridges, and requires turning of the shutters in opposite directions when the initial releases of cartridges are made. For that purpose a gear segment 126 is affixed by means of a set screw 127 to that end of the shaft 123 which protrudes from the end plate 71. The segment 126 meshes permanently with the gear segment 128 of the upper trip arm 129. This arm is freely turnable on the adjacent end of shaft 124, and when the arm 129 is engaged by one of the short pins 130 on the selector wheel 131, the accompanying turn of the selector wheel causes a sufficient turn of the upper shutter 121 in one direction to drop the ball cartridges 64 a short distance. The freely turnable arm 129 is kept in its place on the shaft 124 by a set collar 132 on the outside and a lower trip arm 133 on the inside.

The lower trip arm 133 is secured at 134 to the shaft 124. When this arm is engaged by one of the long pins 135 on the selector wheel 131, the accompanying turn of the wheel causes a sufficient turn of the lower shutter in the direction opposite to that of the shutter 121 to drop the tracer cartridges 64a a short distance. Even though the trip arms are interconnected by virtue of being commonly carried by the shaft 124, there is no community of operation between them. Each arm swings independently of the

other under the impulse of the successively passing short and long pins 130, 135.

The pins 130, 135 have screw tips 136 (Fig. 12) which are driven into threaded holes 137, 138 up to where the pins are shouldered. The respective holes 137, 138 are equally spaced in their respective circumferential zones which are of different diameters. The short and relatively numerous pins 130 occupy the inside zone and actuate only the upper trip arm 129 while the long and relatively sparse pins 135 occupy the outside zone and actuate only the lower trip arm 133. The ratio adopted in the instant illustration is three to one; that is to say, three of the short pins 130 to one of the long pins 135. This ratio interpreted in terms of ammunition means the release of three ball cartridges 64 by the shutter 121 to one tracer cartridge 64a by the shutter 122.

Other serial orders of cartridge release may be provided by properly reorienting the pins 130, 135. The present circumferential spacing of holes 131, 138 will allow such reorientation to release five ball cartridges to one tracer or seven balls to one tracer. By filling all of the holes 137 with pins and leaving the holes 138 empty, only ball ammunition will be released. A pin 139 provides a common stop for the arms 129, 133 in their rest positions (Fig. 8), the arms being urged to the pin-engaging position by the weight of the ball and tracer cartridge columns 64, 64a upon the edges of the offcentered shutters 121, 122. In the case of the arm 129, the requisite motion is transmitted from the shutter 121 by the gearing 126, 128, while in the case of the arm 133, the motion is obtained directly since this arm and the shutter 122 are secured to the same shaft.

Successive turns are imparted to the selector wheel 131 by a pawl and ratchet mechanism 140, 141 shown in Fig. 8. The pawl is pivoted at 142 to the upper end of an erect rod 143 which has a roller 144 at its lower end. This roller rides a cam 145 (Fig. 3) which is flanged at 146 for attachment to the ramming slide wall 96 on top of the plate 95. The axle 147, on which the roller is rotatably mounted in the fork in the lower rod end, has a pin extension 148. The cam 145 extends lengthwise of the slide 96 and reciprocates with it. Consequently, the horizontal movements of the slide are accompanied by vertical movements of the rod 143 and turning movements of the selector wheel.

A spring 149 keeps the roller 144 down on the cam 145 and thus causes the return stroke of the pawl 140 as the low part of the cam moves under the roller. The respective ends of the spring are anchored to the rod 143 and to a bracket 150 having a tubular portion 151 in which the rod is slidable. The bracket is secured at 152 to the end plate 71 of the magazine. A spring 153, anchored on the rod 143, bears against the pawl 140 to keep the latter in engagement with the ratchet 141.

The ratchet 141 is secured to the selector wheel by screws 154 which extend through the wheel and a hub 155 (Fig. 12) before being driven into the ratchet. The hub revolves upon a shaft 156 which is to be regarded as fixed in matching holes in the end plates 71, 72. Set collars 157 secured to the exposed ends of the shaft prevent the possibility of endwise movement, since one of the collars abuts the plate 72 and the other receives the thrust of a spring plunger 158.

The plunger 158 protrudes from the open end of a barrel 159 which houses a spring 160. The

spring abuts the closed end of the barrel and the inner end of the plunger. The outer rounded end of the latter engages successive recesses 161 which match the radial positions of the ratchet teeth, thereby fixing temporarily the positions of the selector wheel.

For the purpose of momentarily stopping the selector wheel 131 during a break-link operation, use is made of a lever 162 (Fig. 8) and a connecting link 163 between the levers 162, 112. The lever 162 is pivoted at 164 to the bracket 73, the free end of the lever being directed toward the roller 144 and having a lug 165 underlying the pin 148. When pressing the break-link lever 112 down at the limit of the ramming stroke of the slide 97, the lug 165 moves up and under the pin 148 which then is elevated because of the rod 143 being at the top of its stroke, thereby supporting the pawl 140 in the up position as long as the pin 117 rides the ledge 111. The selector wheel 131 simply remains idle during the ensuing idle ramming stroke, thereby avoiding the release of an extra round.

The operation of the machine is summarized as follows: Each inward stroke of the slide 97 (Fig. 12) drives one of the cartridges in the feed chamber 10, whether ball or tracer, into hinging position between a pair of links 46, the block 75 (Fig. 6) providing the abutment for the links. The exception occurs when the lever 112 is pressed down for a break-link operation. On each ramming stroke of the slide 97 the cam 145, which gradually becomes higher toward the trailing edge of the slide, raises the rod 143 and moves the pawl 140 to the dotted position C in Fig. 8, imparting a one-twenty-fourth turn to the selector wheel. The number of teeth in the ratchet 141 equals the number of pins 130, 135 in the two circumferential planes in the rim of the wheel, so that the angular displacement of the ratchet by one tooth results in a movement of the wheel an amount equal to the circumferential distance between pins.

Successive pins end their advance in positions against either the trip arm 129 or 133. Fig. 8 shows one of the long pins 135 against the trip arm 133 of the lower release shutter 122, the sequences in Figs. 9, 10 and 11 illustrating the ensuing occurrences in the magazine 53 when motion starts. Upon advance of the engaging pin 135 from the position in Fig. 8 to the position D in Fig. 10, the clockwise turn of the lower shutter from its position in Fig. 9 to that in Fig. 10 allows the lowering of the column of tracer cartridges 64a. The cartridge E which rests on the top edge of the shutter 122 in Fig. 9 then drops into the trough of the shutter where it rests until the pin 135 clears the arm 133 as in position F (Fig. 10).

The weight of the column turns the shutter and arm counterclockwise to the original position (Fig. 11), discharging the tracer cartridge E, which then gravitates to the feed chamber 10, and checking the remainder of the column at the upper edge of the shutter. Releases of cartridges on each side of the magazine occur on the power stroke of the slide 97 simultaneously with a ramming stroke. Ample force is thus available to turn the respective shutter against the weight of the superimposed column of cartridges.

The action just described is repeated as each of the succeeding three short pins 130 moves the arm 129. The motion is transmitted to the shut-

ter 121 by the gearing 128, 126 with the same effect, namely, the dropping of the bottom cartridge, the catching thereof in the trough of the shutter and then the discharge thereof across the lower edge of the shutter. Since the selector wheel is adapted to supply a cartridge to the feed chamber 70 with each ramming stroke, it is desirable to suspend the function of this wheel when the slide 97 makes an idle stroke and it becomes necessary to break the belt. Were this provision not made, the outlet 69 would eventually become unduly loaded.

The invention herein described may be manufactured and used by or for the Government of the United States of America for governmental purposes without the payment of any royalties thereon or therefor.

I claim:

1. In a cartridge feeding mechanism, a freely rockable shutter having the weight of a cartridge imposed off center thereon thereby to rock the shutter to normal cartridge supporting position, and means to counter rock the shutter to cartridge-displacing but intercepting position in readiness for discharge upon shutter gravitation to the original position.

2. In a feeding mechanism, a freely rockable trough-shaped shutter supporting a load on one edge, the weight of the load causing the shutter to gravitate to normal supporting position, and means to positively rock the shutter counter to its free-rocking tendency, to displace the load from said edge and intercept it in the trough in readiness for discharge therefrom upon shutter gravitation to the original position.

3. In a cartridge feeding mechanism, a freely rockable shutter having an off-center turning axis, stop means to prevent turning of the shutter under weight of a load imposed on one edge of the shutter, and means to turn the shutter away from the stop means, displacing the load from said edge and intercepting it by the body of the shutter for subsequent discharge upon gravitation of the shutter to the original position.

4. In a cartridge feeding mechanism, a hopper to contain columns of superimposed cartridges, turnable shutters offcentered in the hopper, each shutter comprising a downwardly directed trough bearing the weight of the respective cartridge column on the upper edge, a stop common to both shutters normally holding them in their supporting positions, and means to turn the shutters away from said stop in a prearranged order against the weight of the respective columns to release the lowermost cartridges into the respective troughs.

5. In a cartridge feeding mechanism, a magazine having a pair of hoppers, a pair of shutters which are centralized in the magazine and are directed oppositely to adjacent hoppers, and means for moving the shutters in a prearranged order and in opposite directions to cause releases of cartridges supported thereby.

6. In a cartridge feeding mechanism, a magazine having a pair of hoppers, a pair of axially rockable shutters centralized in the magazine and directed oppositely to adjacent hoppers to support individual columns of cartridges, a pair of arms, one arm being fixed with the axis of one shutter, the other arm being turnable on the axis of said shutter, means interconnecting said other arm with the axis of the other shutter, and means to move the arms in a prearranged order, thereby to actuate the shutters for the release of the cartridges.

7. In a cartridge feeding mechanism, a magazine having a pair of hoppers, a pair of shutters to support individual columns of cartridges, actuating means for the shutters including an arm for each shutter, said arms being of different lengths, stop means against which the arms are commonly urged by force of the weight of the cartridge columns upon the shutters, and means moving in different planes, respectively, to reach the respective arms and displace them from said stop means in a prearranged order.

8. In a cartridge feeding mechanism, a magazine having a pair of hoppers, a pair of shutters to support individual columns of cartridges, actuating means for the shutters comprising an arm for each shutter, said arms being of different lengths, stop means against which the arms are commonly urged by force of the weight of the cartridge columns upon the shutters, and a turnable selector wheel having pins movable in different circumferential planes to engage and move the respective arms according to a prearranged distribution of said pins.

9. In a cartridge feeding mechanism, a magazine having a pair of hoppers, a pair of shutters to support individual columns of cartridges in the hoppers, actuating means for the shutters comprising an arm for each shutter, the arms being of different lengths, common stop means for the arms, a turnable selector wheel having pins movable in different circumferential planes to engage and move the respective arms according to a prearranged distribution of said pins, and means to move the wheel with a step motion.

10. In a cartridge feeding mechanism, a magazine having a pair of hoppers, a pair of shutters to support individual columns of cartridges in the hoppers, a shaft for each of the shutters, a selector wheel having a rim, a plurality of pins of different lengths, means by which pins of similar lengths are attached to the rim in individual circular series and in prearranged sequential order, an arm secured to one of the shafts and extending into the path of one of the series of pins, an arm loose on said one shaft, being located to one side of said secured arm and extending into the path of another one of the series of pins, means operatively connecting said loose arm with the other shaft, and means to move the wheel with a step motion.

11. In a cartridge feeding machine, a hopper to contain a quantity of cartridges, a shutter for releasing a cartridge, a pin mechanism for intermittently actuating the shutter, a pawl and ratchet device for operating the pin mechanism, and a cam periodically actuated to operate the pawl.

12. In a cartridge feeding machine, a pin and shutter arrangement for releasing single cartridges for gravitation, a reciprocable pawl and turnable ratchet for operating said arrangement with a step motion, means optionally movable into position to intercept the gravitating cartridges, and means actuated by the intercepting means to hold the pawl in an inactive position thereby to suspend operation of the pin and shutter arrangement.

13. In a cartridge feeding mechanism, a shutter for releasing individual cartridges, an operating arm for the shutter, a wheel having pins following a prescribed path and successively engaging the arm to intermittently actuate the shutter, a pawl and ratchet mechanism by which measured step motions are imparted to the wheel, the ratchet having spaced recesses, and spring-

actuated means engaging succeeding recesses to temporarily fix the position of the pin wheel at the end of every step motion.

14. In a cartridge belting machine, a chute along which a belt of linked cartridges is advanced with a step motion, spring-actuated plugs bearing down on the belt, and supporting means for the plugs including tubes which are spaced so as to cause the plugs to bear on the crest of one link and in the valley of an adjacent pair of links at the end of each step motion.

15. In a cartridge feeding mechanism, a hopper to contain a column of cartridges, a shutter in the hopper having a turning axis off-centered from the shutter, thereby enabling rocking of the off-centered shutter in one direction toward a hopper wall contiguous to the shutter under the weight of the column, means limiting the turning of the shutter in said direction, resulting in a temporary jamming and supporting action of the shutter for the column, and means to counter-rock the shutter against the weight of the column for the release of the bottom cartridge and its momentary interception between said wall and the shutter in its counter-rocked position.

16. In a cartridge feeding mechanism, a hopper to contain a column of cartridges, a trough-shaped shutter in the hopper, having a turning axis off-centered from the trough thereby en-

5
10

abling rocking of the off-centered shutter in one direction toward a hopper wall contiguous to the shutter under the weight of the column, means limiting the turning of the shutter in said direction, resulting in a temporary jamming and supporting action for the column between said wall and one edge of the trough, and means to counter-rock the shutter against the weight of the column for the release of the bottom cartridge and its momentary interception between said wall and the trough of the shutter.
